SCREW HOLDING ATTACHMENT FOR
SCREW DRIVERS

Harold E. Noffsinger, Salt Lake City, Utah

Application October 14, 1950, Serial No. 190,107

1 Claim. (Cl. 145—50)

1

This invention relates to a screw-holding attachment for screw drivers, and has for its principal object the provision of a small, light-weight, simple, and highly efficient device which can be slipped over a conventional driver shank without requiring changes in the shank, and which will firmly hold a screw of any type firmly in engagement with the bit of the screwdriver so that the screw may be inserted and tightened with the use of but a single hand.

Another object of the invention is to so construct the device that it can be released from the screw or from the screw driver shank with the same hand which was used for tightening the screw—in other words, to provide a screw-holding attachment for screw drivers which can be installed, renewed, and operated in all of its phases by one hand so that the other hand will be free for other uses.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side view of a conventional screw driver, illustrating the improved screw-holding attachment supporting a typical screw thereon;

Fig. 2 is a similar view, illustrating the position of the operator's hand when releasing the device from the screw after the latter has been threaded partially into place;

Fig. 3 is a similar view, illustrating the attachment completely released from the screw, with the screw driver freed for the final tightening of the screw;

Fig. 4 is a longitudinal section through the improved screw-holding attachment, taken on the line 4—4, Fig. 5, in which the positions of a screw driver shank and screw are illustrated in broken line;

Fig. 5 is a front end view of the improved attachment; and

Figs. 6, 7, and 8 are cross-sections therethrough, taken on the lines 6—6, 7—7, and 8—8, respectively.

In the drawing, the shank of a conventional screw driver is indicated at 10, with its handle at 11 and bit portion at 12. A typical screw is illustrated at 13. The attachment is designed to be

slid over the bit extremity of the shank 10 and to retain itself in place thereon until manually released.

The attachment comprises a cylindrical barrel 14, one extremity of which is open. The other extremity of the barrel is partially closed by an inwardly extending, arcuate, C-shaped flange 15 having a central opening for the reception of the screw 13. The side of the barrel between the block 16 and the flange 15 is cut away, as indicated at 28, opposite the open side of the C-shaped flange 15.

A relatively thick partition block 16 is formed in the barrel 14 in spaced relation to the flange 15. A screw driver shank passage 17 extends axially through the block 16.

A sliding plug 18 is inserted in the open extremity of the barrel 14 and terminates exteriorly of the barrel in an enlarged, knurled head 19. The head 19 is also provided with a screw driver shank passage 20. The inner extremity of the plug presents a flat surface at right angles to the plug axis. The longitudinal sliding movement of the plug 18 is limited by means of a set screw 21 threaded through the barrel 14 and extending into an axially elongated receiving slot 22 in the plug.

A compression spring 23 is positioned between the partition block 16 and the plug 18. The compression spring acts against the plug 18 and against a plurality of clamping washers 24, two being shown. The clamping washers are formed from relatively thick, hardened steel preferably having a thickness of approximately one-sixteenth of an inch. The clamping washers are provided with axial openings 25 of a diameter slightly in excess of the diameter of the expected screw driver shank 10, and each is provided with an outwardly extending lever tongue 26 which projects through an opening 27 in the wall of the barrel 14.

In use, the attachment is slid over the extremity of the shank 10. The head of the screw 13 is placed in the cut-away 28 of the barrel, with its threaded extremity extending through the central opening in the flange 15, and with the bottom of the screw head resting on the flange. The entire attachment is then pulled toward the handle 11 to firmly set the bit portion 12 of the screw driver in the receiving slot of the screw 13.

As the holding attachment is forced toward the handle to grip the screw, the locking washers 24 will turn to a substantially right angle position 55 with relation to the shank so that the latter can

slide freely therethrough. When released, the attachment cannot move toward the screw 13, since any movement in this direction tends to tilt or cock the washers at an angle to the axis so that their openings 25 will grip the screw driver shank.

It will be noted this tilting or cocking is facilitated by the tongues 26 which project outwardly through the opening 27. Any forward movement of the barrel with relation to the washers 24 will cause the tongues to act in the nature of tilting levers to tilt the washers to their gripping positions.

The screw is now inserted in place in the work and rotated until its head approaches the work surface. The operator now slides his hand forwardly along the screw driver shank 10 and forces the head 19 of the plug 18 forwardly with his thumb while gripping the shank 10 and handle 11 with the fingers, as shown in Fig. 2. This causes the flat inner end of the plug 18 to be forced against the washers 24 to swing them to the right angle or releasing position, which allows the entire attachment to move forwardly sufficiently to release the head of the screw 13.

The attachment is now removed from the screw, the head of the latter exiting through the cut-away 28 of the barrel. The entire attachment is then pulled back along the shank toward the handle to expose the bit portion 12 of the shank, as shown in Fig. 3, and the screw driver is reinserted to turn the screw to its final position.

When not desired for use, the entire attachment can be pushed from the shank by pressure on the head 19, or can be pulled back onto the shank to a position adjacent the handle 11, where it will automatically retain itself in place.

While the attachment has been described as moving forward to release the screw, there are times the attachment cannot move forward due to proximity of the work. In such cases the screw driver shank will, of course, move rearwardly to release the screw without movement of the attachment.

While the device has been described as applied to a straight bit screw driver, it could, of course, be used on a "Phillips" type screw driver or any other type, and would operate with equal efficiency.

While a specific form of the improvement has been described and illustrated herein, it is to be understood that the same may be varied, within the scope of the appended claim, without departing from the spirit of the invention.

Having thus described the invention, what is claimed and desired secured by Letters Patent is:

A screw-holding attachment adapted to be positioned on the shank of a screw driver adjacent the bit extremity of the latter, comprising: a tubular barrel; an inwardly extending, C-shaped flange partially closing the outer extremity of said barrel to receive a screw; a partition block formed in said barrel adjacent the flanged extremity thereof, the side of said barrel being cut away between said block and said flange, said block having an axial passage for the shank of a screw driver; a tubular plug positioned in, projecting outwardly from, and closing the other extremity of said barrel, said plug being provided with a coaxial screw driver passage and being free to move longitudinally of both said shank and said barrel; means for limiting the longitudinal movement of said plug in said barrel; a tiltable clamping washer positioned in said barrel between said block and said plug and having an axial opening at right angles to the plane of the washer for the passage of said screw driver shank, the inner extremity of said plug being at right angles to the axis thereof; a spring acting between said washer and said block and urging the former to a tilted gripping position on the shank, said plug being positioned so that its inner extremity will contact said washer when the plug is forced inwardly to swing the washer to the right angular released position; and an outwardly extending tongue formed on one edge of said washer and extending into a receiving opening in said barrel so that relative movement between said barrel and said washer will tilt said washer about said tongue to and from a position at right angles to said shank the length of said tongue being substantially equal to the thickness of said barrel.

HAROLD E. NOFFSINGER.
